UNITED STATES PATENT OFFICE.

WILLIAM C. FREE, OF CHICAGO, ILLINOIS, ASSIGNOR TO ILLINOIS
SEWING MACHINE COMPANY, OF CHICAGO, ILLINOIS, A CORPO-
RATION OF ILLINOIS.

DESIGN FOR A SEWING-MACHINE CABINET.

SPECIFICATION forming part of Design No. 36,150, dated December 2, 1902.

Application filed October 22, 1902. Serial No. 128,355. Term of patent 7 years.

To all whom it may concern:

Be it known that I, WILLIAM C. FREE, a citizen of the United States of America, residing at Chicago, in the county of Cook and State of Illinois, have invented and produced a new, original, and ornamental Design for Sewing-Machine Cabinets; and I do hereby declare the following to be a full, clear, and exact description of the same, reference being had to the accompanying drawing, forming a part thereof.

The accompanying drawing is a perspective view of my new design for sewing-machine cabinets.

The design consists in a cabinet substantially of the configuration shown.

The cabinet comprises the plane ends A and front B, having its upper portion curved inward and its lower portion curved outward, as shown. Above and adjacent to the upper end of the front B is a lintel C. Below and adjacent to the lower end of the front B is a

threshold D, supported by a plane base E and the conventionally-carved ornamental animal-feet F. Conventionally-carved ornamental leaves G are also placed on the lower end portion of the front B above the feet F. Immediately over the lintel C is a plane drawer-front H, flanked by pilasters I.

The cabinet proper is surmounted by a cover comprising the plane top J, plane end pieces K, ogee front L, and back rail M.

Having described my invention, what I claim as new, and desire to secure by Letters Patent, is—

The ornamental design for a sewing-machine cabinet herein shown and described.

In testimony whereof I have signed my name to this specification in the presence of two subscribing witnesses.

WILLIAM C. FREE.
